(57) **CLAIM**

The ornamental design for a shoe heel counter as shown and described.

DESCRIPTION

FIG. 1 is a rear perspective view of a shoe heel counter according to our new design;

FIG. 2 is a right side elevation view thereof;

FIG. 3 is a left side elevation view thereof; and,

FIG. 4 is a rear elevation view thereof.

The broken lines in the figures show portions of the shoe that form no part of the claimed design.

1 Claim, 4 Drawing Sheets

FIG. 1

FIG. 2

FIG. 4
